UNITED STATES PATENT OFFICE.

EDWARD A. LITTS, OF SIOUX CITY, IOWA.

CLAMP-BRACKET.

No. 818,457.

Specification of Letters Patent.

Patented April 24, 1906.

Application filed May 23, 1905. Serial No. 261,917.

To all whom it may concern:

Be it known that I, EDWARD A. LITTS, a citizen of the United States, residing at Sioux City, in the county of Woodbury and State of Iowa, have invented certain new and useful Improvements in Clamp-Brackets, of which the following is a specification.

This invention relates to a clamp-bracket designed for removably applying an awning to the cab-windows of locomotive-engines without requiring a rod or other devices commonly employed for this purpose and which is easily removed and adapted to be reversed or shifted from engineer's side of the cab to the fireman's side and which is portable and capable of being carried in a grip or other convenient manner.

For a full description of the invention and the merits thereof and also to acquire a knowledge of the details of construction of the means for effecting the result reference is to be had to the following description and accompanying drawings, in which—

Figure 1 is a perspective view of an awning embodying the invention, parts being broken away to disclose the brackets. Fig. 2 is a detail view of a clamp-bracket on a larger scale. Fig. 3 is a detail view of a slide. Figs. 4 and 5 are front detail views of modified forms of the bracket. Figs. 6 and 7 are detail views of different forms of awning-clamps.

Corresponding and like parts are referred to in the following description and indicated in all the views of the drawings by the same reference characters.

Figs. 1 and 2 show the preferred construction of the awning-clamp bracket, the same consisting of the frame 1, slides 2, and clamp members 3, which are pivoted at their inner ends to the respective slides 2. Each slide 2 is provided with a projection 20, transversely widened to receive an end portion of a right and a left hand threaded rod 21. The middle portion 22 of the rod is enlarged and preferably formed with openings to receive a handle to admit of the application of force when it is required to rotate the rod to effect movement of the clamp members to cause them to grip the jamb of the window or other part to which the awning is to be fastened. A forked bracket 23, affixed to the frame 1, has its forked members embodying opposite ends of the enlarged portion 22 to hold the rod 21 against longitudinal movement.

In the modification shown in Fig. 4 the clamp-bracket consists of a frame 1, slides 2,

clamp members 3, and operating means therefor. The clamp members 3 are longitudinally curved and are pivotally connected at their inner ends to slides 4, which are adjustably connected with the slides 2 by means of set-screws 5, thereby admitting of adjusting the clamp members with reference to the main slides 2, which are primarily actuated in the operation of the clamp. The clamp members 3 are longitudinally slotted, as shown at 6, and guide-pins 7 pass through the curved slot 6 and direct the free ends of the clamp members when moving outward or inward according as the slides are forced apart or drawn together.

As shown in Fig. 4, a single lever 8 is provided for operating the clamp and is pivoted at 9 to the main frame 1, connected by means of links 10 to the slides 2. Movement of the lever 8 in one direction forces the slides 5 apart and imparts a corresponding movement to the slides 4 and the clamp members 3, pivotally connected thereto. Said clamp members, by reason of their curvature and the action of the pins 7 and slots 6 move outward at their outer ends, thereby unclamping the part to which the bracket or device is applied. A movement of the lever 8 in the opposite direction draws the several slides together and results in moving the outer ends of the clamp members 3 inward, whereby the bracket or device is clamped, fastening it to window-jamb.

In the construction shown in Fig. 5 toggle-links 11 connect the slides 2, and upon breaking the joint said slides are drawn together, and upon straightening the toggle-links the said slides are forced apart, with the result that the clamp members are forced outward at their free ends in the manner and for the purpose herein stated.

A clamp member is fitted to the upper end of the bracket or main frame and may consist of a simple clip A, as shown in Figs. 1 and 2, or may be of the form shown in Figs. 6 and 7. In both latter forms the end of the frame 1 is recurved at 14 and is provided with either a set-screw 12, as shown in Fig. 7, or a cam-lever 13, as indicated in Fig. 6. An arm 15 is pivoted to the curved end 14 and is provided with a jaw 16, and a companion jaw 17 is attached to the frame 1 for coöperation with the jaw 16. The jaws 16 and 17 are closed by operating either the set-screw 12 or the cam-lever 13, the latter being held in the adjusted position by means of teeth 18 and a co-

operating pawl 19. The clamps (shown in Figs. 6 and 7) are used when the awning is rodless or has ropes only run through the hem.

5 5 An arm 24 is pivoted to the lower end of each frame 1 and is provided at its outer end with a clamp or clip 25 of any construction, either as shown in Fig. 1 or in Figs. 6 and 7. The awning 26 is provided at the top and 10 bottom edges with a hem in which is fitted a rope, the latter being secured by means of the clips at the ends of the frames 1 and the outer ends of the arms 24.

Having thus described the invention, what 15 is claimed as new is—

1. Means for removably attaching an awning to the jambs of an opening, the same consisting of a pair of oblong frames, one for each jamb, laterally-operable clamps at intervals 20 in the length of each frame for gripping opposite sides of the jamb, means connecting the clamps of each frame for simultaneous operation, and means at opposite ends of the frames for detachable connection therewith 25 of the awning.

2. Means for removably attaching an awning to the jambs of an opening, the same consisting of a pair of oblong frames, one for each jamb, a pair of slides mounted upon each 30 frame, a clamp having adjustable connection with each slide, means connecting said slides for simultaneous operation, and means at opposite ends of the frames for detachable connection of the awning thereto.

35 3. In a device of the character set forth, the combination of a main frame, oppositely-disposed clamp members, slides having said clamp members pivotally connected thereto, other slides, means for adjustably connecting 40 the two sets of slides, and actuating means for

moving the last-mentioned slides outward or toward each other.

4. Means for removably attaching an awning to the jambs of an opening, the same consisting of a pair of oblong frames, clamps at 45 intervals in the length of each frame, operating means, connections adjustably joining the clamps to the operating means, a pivoted arm at the lower end of each frame, and awning-clamps at the upper end of the frames and at 50 the outer ends of the pivoted arms.

5. Means for attaching an awning to the jambs of an opening, the same consisting of a pair of frames, each provided at its upper end with a clamp, and having at its lower end a 55 pivoted arm provided at its outer end with an awning-clamp said frames having clamp devices intermediate of their ends consisting of upper and lower pairs of clamp members and intermediate actuating means.

6. Means for attaching an awning to the jambs of an opening, the same consisting of a pair of frames, each provided at its upper end with a clamp, and having at its lower end a pivoted arm provided at its outer end with an 65 awning-clamp said frames having clamp devices intermediate of their ends consisting of upper and lower pairs of clamp members and intermediate actuating means, the latter consisting of slides having the clamp members 70 attached thereto, operating means, and adjustable connections between the operating means and said slides.

In testimony whereof I affix my signature in presence of two witnesses.

EDWARD A. LITTS. [L. S.]
